MECHANISM FOR MANIPULATING
FLEXIBLE REVETMENT MATS

Frank I. Louckes, Memphis, Tenn.

Application May 2, 1950, Serial No. 159,562

5 Claims. (Cl. 294—117)

(Granted under Title 35, U. S. Code (1952),
sec. 266)

1

The invention described herein may be manufactured and used by or for the Government for governmental purposes, without payment to me of any royalty thereon.

This invention relates to improvements in revetment mats adapted to protect against erosion on levees, river banks, river bottoms, shores, canals and the like, the mats being designed to cover areas of such shores to protect the same against current erosion, wave wash, and other similar destructive elements.

Generally speaking, these revetment mats when placed in location, constitute permanent installations. Therefore, they must be of sufficient weight to prevent displacement or dislocation through current or wave action and they must be sufficiently flexible to enable them to be self-accommodating to irregularities of the shore line. These revetment mattresses are composed of a plurality of flexible sections constructed of flexibly interconnected concrete slabs closely spaced apart, and held together by reinforcing wires which extend continuously from block to block, both longitudinally and transversely, whereby a flexible unit section is produced.

The mattress is assembled by flexibly joining the ends of adjacent sections or squares. The mattress, approximately four feet wide by twenty-five feet long in surface dimensions and about three inches thick, is cast in steel forms divided by a horizontal plane into top and bottom form sections. The bottom form sections are arranged side-by-side with their longitudinal edges practically in contact with adjacent forms and permanently bolted to a base casting slab twenty-five feet wide by indefinite length, depending upon the number of forms in use. The top form sections are removable. Both the top and bottom form sections are each divided into three subsections or "squares," measuring four feet by eight feet four inches, and which, when assembled end-to-end, make up the full form lengths.

In operation, the top form sections are assembled on the bottom forms and the completed forms are filled with concrete, and the top of the concrete is struck off flush with the top of the top form and finished. When the concrete has partially set, just enough so that vertical surfaces will not slough when unsupported, the top form sections are removed. The period of setting seldom exceeds seven and one half hours. When the top forms have been removed and the concrete has substantially fully set, it is lifted from the casting frame by the improved mechanism of the present invention.

2

As is just indicated above, the present invention relates specifically to equipment designed particularly for picking up and stock piling the precast articulated concrete revetment mattress sections, the invention having for one of its objects, the provision of safe and expeditious means for lifting the precast sections of large surface area. A further object of the invention is to provide lifting equipment for lifting such sections of large area by means of embedded reinforcements, access to which is provided by openings formed in the top surface of the sections at the time the concrete is poured into the molds.

A still further object of the invention is to provide lifting means for a flexibly articulated concrete square of a revetment mattress which will accomplish the lifting of the square easily and free from distortional stresses during the lifting and stock piling of the concrete square.

Further objects of the invention will become apparent as the description proceeds, and the features of novelty will be pointed out in particularity in the appended claims.

It will be understood that a flexible revetment mattress is composed of flexibly interconnected concrete slabs of thin cross-section, these slabs being interconnected into squares of large surface area, as has been pointed out above. There are no protruding parts by which it can be picked up, nor can it be picked up by its edges; and as the cast squares are removed from the casting slab when they are less than twenty-four hours old, they must be handled carefully to avoid unequal lifting strains which would result in breakage. The improved lifting mechanism of the present invention is simple in construction and operation, but it is adapted for heavy duty service.

The improved lifting mechanism of the present invention will be understood more fully by reference to the accompanying drawings, in which:

Fig. 1 is a side elevation of a lifting mechanism, embodying the principles of the present invention, the mechanism being shown as being positioned over a revetment mattress square which is to be lifted by the mechanism of the invention and manipulated thereby;

Fig. 2 is a transverse sectional elevation of the construction of Fig. 1, the view being taken on the line II—II of Fig. 1, looking in the direction of the arrows;

Fig. 3 is a view similar to Fig. 2, but showing the lifting device of the invention lowered into operative position on the revetment square;

Fig. 4 is a fragmentary plan view of the lifting device of this invention;

Fig. 5 is a fragmentary longitudinal sectional elevation taken on the line V—V of Fig. 4, looking in the direction of the arrows; and

Fig. 6 is a fragmentary perspective view of the improved mechanism of the invention, the device being shown in raised position above the revetment square.

Referring more particularly to the drawings, reference character A designates generally a revetment "square" which is composed of concrete slabs 8 which have been cast around reinforcing wires 10 and 12. The wires 10 define connections between adjacent pairs of the precast slabs 8, the end loops 11 thereof being exposed to permit the tying thereto of corresponding end loops of an adjacent similar square (not shown) assembled to the square A in end-to-end relation for increasing, as may be needed, the width of the assembly revetment mattress. These wires 10 extend longitudinally through adjacent slabs 8, but are transversely extending with respect to the assembled square. The slabs 8 are cast in such manner that the top half of the slabs forms a substantially square end butt which overhangs the lower half of the slabs, thereby forming a recess in which the connecting loop 11 is received. The wires 12 extend longitudinally through the assembled mattress section or square A and form flexible connections or hinges between adjacent slabs 8 that are assembled in side-by-side relation. These wires 12 terminate in eye-loops 14 which are enclosed in end recesses 16 and are adapted to be interconnected with similar end loops of an adjacent square assembled to the square A in side-by-side relation. In the illustrated form of the revetment square, the slabs 8 are cast with V-shaped sides which can be brought into close engagement one with another for preventing objectionable separation of the adjacent slabs.

When the slabs 8 are cast, they are cast with lateral stirrup openings 18 therein, which openings register with the wires 12 and permit access thereto of lifting instrumentalities to be described hereinafter in detail, for lifting the cast and assembled square out of the casting molds, and for stock piling.

This lifting mechanism forms the subject matter of the present invention, and is indicated generally by B.

This lifting mechanism comprises a frame composed of a longitudinally extending I-beam 20, the web of which is disposed vertically, with the upper and lower flanges 22 and 24, respectively, substantially horizontal.

To the underside of the flange 24, there are welded or otherwise rigidly secured, spaced transverse beams 26, which are reinforced by diagonal braces 28, welded to the web of the I-beam 20, and to the transverse beams 26, these latter having mounted thereon the longitudinally extending lateral angle beams 30, from which project outwardly spaced brackets 32, the brackets being the same number on each side and in opposite alignment. These brackets pivotally carry the depending arms 34, the pivotal connections being shown at 36. The depending arms 34 terminate in inwardly directed hooks 38 that are adapted to enter stirrup openings 18 in the slabs 8, and to engage beneath the wires 12.

Mechanism is provided for actuating these arms 34. This mechanism includes spaced transverse I-beams 40 that are welded to the underside of the lower flange 24 of I-beam 20. Depending from the transverse I-beams 40 are

bearing brackets 42, which form bearings for a shaft 44 that extends through the length of the machine. On this shaft 44, and intermediate opposite lateral arms 34, are the spaced crank discs 46 to which are pivotally secured, as indicated at 48, oppositely extending lever arms 50 that are pivoted to the laterally oppositely depending arms 34, as is indicated at 52. The arms 34 are interconnected in groups by the angle bars 54 welded thereto, the drawings showing the arms 34 to be interconnected in groups of five, although this specific number is not critical. However, it enables the reduction in the number of the crank discs 46, so that only two of the crank discs 46 and the oppositely pivotally mounted lever arms 50 will be required for the actuation of each interconnected group of the depending arms 34, there being one of these assemblies at each end of each group so that all of the depending arms 34 of each group will be actuated simultaneously.

The pivotal connections 48 between the lever arms 50 and the crank discs 46 are somewhat offset, as shown, and the arms 50 move the arms 34 inwardly and outwardly responsively to corresponding rotary motions of the crank discs 46, responsively to turning the shaft 44 by actuation of the turning lever 56, which is keyed to the shaft 44. One of these turning levers is mounted on each end of the shaft 44, so that the depending arms 34 may be actuated by an operator at either end of the machine. Also, at either end of the machine, there is welded to the bottom flanges of the lateral beams 30, a transversely extending angle beam 58, to the depending flange of which is secured thereto an angle member 60, there being such angles mounted in corresponding positions on both sides of the machine. To these angle members 60 are secured bearing brackets 64 for bearing rollers 66. Also, the I-beam 20 carries spaced eye-bolts 68, for receiving suspension chains 70 that are received in a ring 72 which is adapted to receive a hook 74 which is suspended from a lifting crane, not shown. Adjustably mounted on one of the longitudinal lateral angles 30 is a vertical end guide bar 76 extending loosely through a socket 78 carried by a horizontally extending slide bar 80 which rides on its angle bar 30. The guide bar 76 is provided with a flanged head 81. A similar lateral guide bar 82 is provided which is slidable in its socket 83 carried by one of the transverse bars 40 at each end of the form and has a flanged head 85, these guide bars 76 and 82 being adapted to engage the revetment square A for positioning the handling mechanism relative to the square. Chains 84 suspended from the ends of the lateral angle bars 30, and having a hook 86 on the end thereof, are provided for supporting the end slabs of the mat during lifting and moving of the mat, by insertion of the hooks 86 in the end loops 14 of the wires 12.

In operating the present improved lifting device, it is placed over the concrete revetment square A and centered by guide bars 76 and 82; and the hooks 38 are brought into registry with the stirrup openings 18, this manipulation being effected by the crane from which the lifting device is suspended. The lifting device then is lowered onto the mat square A with the hooks 38 in the stirrup openings 18 and below the wires 12. Shifting the lever 56 from the position shown in Fig. 2 to that shown in Fig. 3 causes the hooks 38 to be forced inwardly and slipped under the reinforcing wires 12, and since the bearing rollers

66 are in engagement with the top surface of the mat square A, the rollers 60 permit the frame to be shifted on the mat square A responsively to the pincers action of the hooks 38 against the wires 12, thereby automatically centering the lifting device on the mat square A relative thereto.

When the lifting device and mat square A are lifted and the squares are placed on a stock pile, the guide bars 76 and 82 are employed to center each square, the lifting device being swung over the stock pile until the guides strike the side and end of the pile and the section is lowered to its correct position. The sockets permit the guide bars to slide up when the lifting device is lowered on a square to be picked up, but the bars at once drop back into their sockets when the lifting frame is picked up. These guides also facilitate the proper positioning of the lifting device over the cast mattress sections or squares so that the arms 34 will be brought easily into registry with the openings 18.

While the foregoing description and drawings apply to a preferred embodiment of lifting instrumentalities for precast concrete slabs or other concrete sections, such as the flexibly articulated revetment mat squares, details may be made without departing from the inventive concept, and that therefore it will be understood and desired to embrace within the scope of invention such modifications and changes as may be necessary to adapt it to varying conditions and uses as defined by the appended claims.

Having thus described my invention, what I claim as new and wish to secure by Letters Patent is:

1. Mechanism for lifting and stacking cast squares of flexible revetment mats composed of concrete slabs flexibly interconnected by flexible reinforcing means and having openings formed therein in registry with the reinforcing means, the said mechanism comprising a frame adapted to be positioned over the shape to be manipulated, a plurality of oppositely disposed spaced parallel lifting arms vertically depending from the frame and pivotally suspended therefrom adjacent to upper ends of the arms, the said arms being adapted to enter the openings in the square and terminating in lifting hooks adapted to engage the flexible reinforcing means exposed by the openings in the square for lifting and carrying the square to a stacking station, an operating shaft extending longitudinally of the frame and carried by the frame intermediate the lifting arms, tie bars secured to selected members of the lifting arms for operatively tying together the lifting arms into a series of unitary groups thereof, operating discs on the shaft at each end of each group of the lifting arms, oppositely extending actuating lever arms interconnecting each of the discs with opposite terminal lifting arms of each of the groups thereof, the lever arms having inner ends secured to the operating discs in vertical diametrically opposite relation, operating levers for the said shaft at each end of the shaft for operating the shaft and the groups of lifting arms simultaneously, end and side guide bars depending from the frame for engaging corresponding ends and sides of the square with the lifting arms in vertical alignment with the openings, and guide rollers carried by the frame for engagement with the square when the frame is lowered with the lifting arms entering the openings in the square, the said guide rollers centering the frame on the square 75

responsively to engagement of the lifting hooks on the said lifting arms with the flexible reinforcing means interconnecting the slabs of the revetment square.

- 5 2. Mechanism for lifting and transporting massive shapes such as concrete slabs of large areas including revetment mat squares composed of slab-like units of reinforced concrete flexibly interconnected by flexible reinforcing fabrics and having lifting openings symmetrically disposed relative to the shape and in longitudinal and transverse alignment and coincident with strands of the reinforcing fabric which act as means enabling lifting and manipulating the shapes, 10 15 20 25 30 35 40 45 50 55 60 65 70 75
- 15 the said mechanism comprising a frame suspended above the shape to be lifted, the frame including a suspension beam and lateral beams rigidly secured to the suspension beam and extending longitudinally thereof, a plurality of lifting arms connected pivotally to the lateral beams and freely depending therefrom, the said arms corresponding in number and spacing to the lifting openings in the shape and being adapted to enter the said openings when in registry therewith, the lifting arms terminating in lifting hook members for engaging portions of the reinforcing fabrics extending through the openings, end and side guide means depending from the frame and rigidly connected with the frame for engaging ends and sides of the shape responsively to the frame being centered relative to the shape with the pivoted lifting arms in aligned registry with the lifting openings in the shape while the frame is suspended above the shape and the lifting arms and hook members thereon are in position to engage the said portions of the reinforcing fabrics within the lifting openings when the frame is lowered, rigid means interconnecting selected numbers of the lifting arms into a series of rigid unitary groups, there being a series of such groups of the arms on opposite sides of the frame in direct opposition to one another, while the groups on each side of the frame are in spaced alignment, and mechanism carried by the frame and interconnected with the rigid unitary groups of lifting arms for producing simultaneous and equal operation of each group, the said mechanism also producing equal and opposite movement of opposite groups for producing simultaneous lifting engagement of the hook members of each group relative to the reinforcing fabrics of the squares for effecting equal and uniform lifting and transport movements of the shape without imparting distortional stresses to any portion thereof.
3. Mechanism for lifting and shifting from one station to another cast concrete shapes of large area such as revetment mat squares composed of concrete slabs flexibly interconnected by flexible reinforcing means and having lifting openings formed therein in registry with the reinforcing means, the said mechanism comprising a continuous frame freely suspended over the shape and being movable vertically relative thereto, the frame having a length substantially coextensive with that of the said shape, a plurality of oppositely disposed parallel lifting arms depending vertically from opposite sides of the frame and pivotally interconnected thereto and adapted to enter the lifting openings in the shape responsively to lowering the frame for engaging the said arms with the reinforcing means for the shape exposed in the said openings, rigid means rigidly secured to a selected plurality of the lifting arms and interconnecting them into unitary

rigid groups extending serially along the frame, a shaft carried by the frame longitudinally thereof, a disc crank directly mounted on the shaft at each end of each rigidly connected group of the lifting arms, the said arms terminating at their lower free ends in hook members adapted to liftingly engage the reinforcing means responsively to entry of the arms into the lifting openings of the shape when the frame is lowered relative to the shape so that the hook members may liftingly engage the reinforcing means extending through the openings, oppositely extending approximately equal operating links pivotally connected to the disc cranks at equal distances from the shaft and on diametrically oppositely extending radii of the discs and also pivotally connected to the opposing unitary groups of lifting arms for effecting equal and opposite movement to opposite lifting arm groups while simultaneously and equally actuating the aligned groups on each side of the frame, and an operating lever mounted on the shaft for turning the shaft and disc cranks for equally and simultaneously operating all of the groups of lifting arms.

4. Mechanism for lifting and manipulating cast concrete shapes of large area such as revetment mat squares composed of concrete slabs flexibly interconnected by flexible reinforcing means and having lifting openings formed therein in registry with the reinforcing means, the said mechanism comprising a continuous frame suspended over the shape to be manipulated and having a length approximating that of the shape, a plurality of oppositely disposed parallel lifting arms vertically depending from each side of the frame and pivotally interconnected thereto and adapted to enter the openings in the shape responsively to lowering the frame relative to the shape, the said arms terminating at their lower free ends in inwardly directed lifting hooks adapted to liftingly engage the underside of the flexible reinforcing means exposed by the lifting openings in the shapes, means rigidly connecting selected numbers of aligned lifting arms into series of integral groups, a shaft carried by the frame extending longitudinally thereof, spaced disc crank members on the shaft, there being one such disc member adjacent to each end of each integral group of the depending lever arms, oppositely extending actuating links pivotally connected to the disc members at diametrically opposite pivotal mountings and also pivotally connected to corresponding ends of opposite integral groups of the lifting arms, the said links equally and oppositely actuating the said opposite integral groups of depending arms into and away from lifting engagement between the hook members and the reinforcing means of the shape, an operating lever on the shaft for turning the shaft and disc members thereon, thereby effecting equal and simultaneous movement of each group of depending arms as a unit, end and side guide bars rigidly depending from end and side members of the frame for engaging the shape endways and laterally thereof responsively to centering the frame relative to the shape, and roller means carried by the frame for further adjustment of the frame relative to the shape respon-

sively to lowering the frame relative to the shape and entry of the lifting arms into the opening in the shape for relieving unequal pressures on the said arms of each integral group thereof resulting from any slight misalignment of any group of the arms with corresponding openings in the shape for relieving such unequal pressures and equalizing entry of the depending arms of each group into the openings for uniformly engaging the hook members on the arms with the reinforcing means of the shape exposed in the said openings for imparting unstressed lifting and transport movements to the shape.

5. Mechanism for lifting and moving concrete revetment mats composed of individual concrete slabs flexibly interconnected by flexible reinforcing means and having symmetrically disposed lifting openings at each side of contiguous slabs, the mechanism comprising a frame including a suspension beam and longitudinally extending opposite side beams rigidly secured to the suspension beam, oppositely disposed pivotally mounted lifting arms depending from the side beams, the arms depending from each side beam being in spaced parallel alignment and substantially directly opposite to the arms depending from the opposite side beam, the said arms corresponding in number and spacings to the lifting openings in the said slabs and being adapted to enter the said openings responsively to symmetrical placement of the frame relative to the slabs and revetment mat, rigid connecting bars secured to a plurality of the aligned arms and connecting the said plurality of arms into an integral group, such group on one side of the frame being opposite to a corresponding group on the opposite side of the frame, an operating shaft for the groups carried by the frame, operating lever means on the shaft for the said groups, there being such lever means for each end of each group, the said lever means simultaneously and equally operating the groups on each side of the frame as a single unit while also equally and oppositely actuating the corresponding opposite groups, whereby all lifting arms are simultaneously and equally operated for equal distribution of the weight of the revetment mat between the lifting arms during shifting of the mat from one station to another while preventing any substantial relative displacements between the individual slabs during the shifting.

FRANK I. LOUCKES.
